UNITED STATES PATENT OFFICE.

ARNOLD PHILIPP, OF CHICAGO, ILLINOIS.

SAFETY PIN.

Application filed April 2, 1927. Serial No. 180,385.

This invention relates to a pin of the type commonly referred to as a safety pin and particularly to a pin of this character which is so constructed that the accidental opening of the pin after it has been clasped is obviated.

The object of the invention is the provision of a pin of the above noted character having spring actuated means for holding the needle of the pin in locked position.

One of the features of the invention is a safety pin having the needle part or pin proper thereof formed for bodily movement relative to the back of the pin and tension means joining the back and needle so constructed as to lock the needle in clasped position or to permit bodily longitudinal movement of the needle to remove the point of the needle from the clasp.

Other features and advantages will appear from time to time as the description of the invention progresses.

It is believed the further disclosure of the invention will be understood most readily from a detailed description thereof taken in connection with the accompanying drawings in which

Fig 1 is a side view of a pin embodying a preferred form of the invention;

Fig. 2 is a view looking at the pin of Fig. 1 from the top of the drawing, and

Fig. 3 is an end view of the pin.

Referring now to the drawings in which like reference characters indicate the same parts in the several figures, 10 indicates the shank or back portion of the pin. In the drawings the back 10 is shown formed of sheet metal U-shaped in cross section although this part of the device may be formed of wire or other suitable material without departing from the spirit of the invention.

The back 10 terminates at one end in a clasp or needle point receiving portion 11.

The sides of the clasp 11 are bifurcated at the tip to form a guide 12, to assist in guiding the point of the needle 13 into the clasp 11.

Integral with the other end of the back 10 are the substantially parallel flanges, 14, 14' between which is mounted one end, 15 of the pin proper, 13. Formed in the flange, 14' near the forward edge is a bayonet slot 16. The portion 15 of the pin is shaped to provide a U-shaped bend 17, which extends through the slot 16 which limits and guides the movement of the portion 15.

Integral with the end of the part, 15 is a curved spring portion, 18, the end of which is secured between the flanges 14, 14' in any desired manner. In the present embodiment 60 a lug, 20, is pressed out of the flanges 14' against which the end of spring, 18, bears. The tension in spring, 18, is such that the needle or pin proper, 13, is urged longitudinally to the left as seen in Figs. 1 and 2 of 65 the drawings, that is, the point of the pin is forced toward or into the clasp 11. The pin is guided to move in a longitudinal direction by the parallel portions of the U-shaped part, 17, sliding in the slot 16. 70

It may be explained here that instead of forming the pin with the U-shaped bend, 17, it may be provided, in any manner, with outwardly extending parallel lugs corresponding to the legs or parallel portions of part, 17. These may be secured to the pin by solder, by being riveted thereto or in any other desired manner. 75

When it is desired to unclasp the pin, the pin or needle part is drawn to the right as 80 seen in Figs. 1 and 2 of the drawings. This may be done by grasping the loop of spring, 18. When the right hand leg of the bend, 17, reaches the end of the slot, 16, the pin is tilted into the position shown in Fig. 1 85 of the drawings. The tension in spring, 18, tends to hold the pin in this position so it will remain unclasped. When, however, the pin is tilted about the left leg of portion, 17, as a pivot until parallel with the 90 back of the pin, the spring acts to force it to the left, as seen in Figs. 1 and 2 so the point of the pin will be seated in the clasp, 11. 95

While in the present embodiment of the invention the actuating spring is shown integral with the end of the needle portion, it is to be understood that the spring may be formed separately therefrom and may be flat, spiral, round or any other desired form so long as it operates to urge the pin to the left as seen in the drawings and also will act to retain the pin in unclasped position. 100

The present invention was particularly designed as a safety pin but its use for other purposes is contemplated. Various modifications in the design and structure of the pin are also contemplated. The invention therefore should be limited only by the scope of the appended claims. 105

Having thus described my invention what I consider to be patentable and desire to 110

secure by Letters Patent of the United States is:

1. In a safety pin, a back portion, a pin or needle portion, a point receiving clasp at one end of said back portion, means at the opposite end of said back portion for automatically guiding and directing said pin into said clasp and a spring joining said pin to said back portion normally urging said pin toward said clasp. 35
2. In a safety pin, a back portion, a pin or needle portion, a point receiving clasp at one end of said back portion, a guide at the opposite end of said back portion for automatically guiding said pin longitudinally and directing it into said clasp and a spring joining said pin to said back portion normally urging said pin toward said clasp. 40
3. In a safety pin, a back portion, a pin or needle portion, a point receiving clasp at one end of said back portion, a flange at the opposite end of said back portion having a slot therein for guiding and directing said pin into said clasp and a spring joining said pin to said back portion normally urging said pin toward said clasp. 45
4. In a safety pin, a back portion, a pin proper or needle portion, a point receiving clasp at one end of said back portion, a flange at the opposite end of said back portion having a slot therein, outwardly ex- 50

tending lugs or legs carried by said pin and slideable in said slot and a spring joining said pin to said back and normally forcing the point thereof toward said clasp.

5. In a safety pin, a back portion, a pin proper or needle portion, a point receiving clasp at one end of said back portion, a flange at the opposite end of said back portion having a slot therein, outwardly extending lugs or legs carried by said pin slideable in said slot, and guiding said pin to move in a longitudinal direction and a spring joining said pin to said back and normally forcing the point thereof toward said clasp. 55

6. In a safety pin, a back portion, a pin proper or needle portion, a point receiving clasp at one end of said back portion; a flange at the opposite end of said back portion having a slot therein, outwardly extending lugs or legs carried by said pin slideable in said slot and forcing said pin to have a longitudinal movement and a spring joining said pin to said back and normally forcing the point thereof toward said clasp, said slot having an offset at one end thereof to permit said pin to swing to unclasped or open position. 60

In testimony whereof I have signed this specification.

ARNOLD PHILIPP.
